UNITED STATES PATENT OFFICE.

ROBERT BROWN, OF FREDERICK, MARYLAND.

IMPROVEMENT IN HARVESTERS.

Specification forming part of Letters Patent No. 40,395, dated October 27, 1863.

To all whom it may concern:

Be it known that I, ROBERT BROWN, of Frederick, in the county of Frederick and State of Maryland, have invented certain new and useful Improvements in Grain and Grass Harvesters; and I do hereby declare that the following is a full, clear, and exact description of the construction and operation of the same, reference being had to the accompanying drawings, in which—

Figure 1 represents a perspective view of said harvesting-machine. Fig. 2 represents a longitudinal vertical section through the same. Figs. 3, 4, 5 represent detached views, herein-after to be referred to. Figs. 6, 7, 8 represent views of the cutting apparatus of my machine.

My invention consists, first, in the combination, with the angular side pieces of the main frame, of two short wheel-axes, which support the driving-wheels of the machine; also, in the combination of clearers, which are attached to the lower sides of the sickles, with the open guard-fingers, having spaces under and to the rear of the cutting-edges of the blades for the purpose of clearing the guard-fingers from damp grass or other material which tends to clog the machine.

To enable others skilled in the art to make and use my invention, I will proceed to describe its construction and operation.

A represents the main frame of the machine, to which the tongue or pole B is rigidly attached. The braces C, which support the seat D, are also secured to this frame. The main frame A consists of the longitudinal bars 1, the shape of which is shown in cross-section at Fig. 4. These side pieces are bolted to the front cross-tie, 2, and are braced together near the rear by means of the braces a b. By this means I obtain a frame of a very simple and cheap construction, which may be made of wrought-iron, and therefore of comparatively light material; but the principal advantage in this construction is that the rear end of the frame is open, and therefore the swinging frame E, to which the cutting apparatus is attached, may be easily secured at almost any point on the bars 1, there being nothing to obstruct its movement at the rear end of the frame. The braces a and b, which are intended to impart steadiness to the main frame, do not interfere with the action of the frame E, as the brace h is above its limit of motion, and the

brace b prevents it from moving downward beyond its intended limit.

The swinging frame E is hung to the stationary shaft or bar F, on which it turns on being raised or lowered by passing over uneven ground, it being supported in its lowest position by the brace b, which prevents it from descending farther than it is intended, according to the construction of the machine. The finger-bar G is secured to the head d of the shaft H by means of the bolt e, and said finger-bar may be raised and lowered by the lever arrangement commonly used in harvesting-machines for that purpose, in connection with a rope or chain, which is secured to the shoe-plate I of the finger-bar, said lever arrangement and one of the driving-wheels being left off on the drawings, as they would cover other parts which it is essential to show thereon.

The axles K of the driving-wheels are secured to the stationary frame A in the following manner: The upper end of the axle is flattened, so as to fit against the horizontal part x of the bar 1, while the butt-end comes up close to the vertical part y of said bar. A stirrup-bolt, g, which enters a corresponding groove on the circumference of the axle, is then passed around it, and is secured to the part x by means of the screw-nuts S. The axle K, being snugly fitted on the parts x and y, cannot move sidewise, and constitutes a cheap and simple construction for harvesting-machines, reducing the weight of the machine by using two short axles instead of one long one. This feature is of great importance in harvesting-machines in which a hinged cutter-bar frame is used within the main frame, as by the application of the two short axles which extend outside of the main frame no part of said axles obstructs the free motion of the inner hinged frame. To raise and lower the grain end of the cutting apparatus for the purpose of regulating the length at which the grain is to be cut, I make the grain-wheel L adjustable and use the following device: M represents the shaft of the swivel-wheel. To this shaft is secured the slotted arc h. The piece i, which supports the grain-wheel L, is pivoted at k to the shaft M, and its arm 3 may be secured at any desired position on the arc h by means of the set-screw 4, which passes through the slot of the arc h. Thus the grain-wheel may be

raised or lowered to cut the grain high or short, and may be secured in any position by means of the set-screw 4.

The cutting apparatus of my machine is represented in Figs. 6, 7, and 8. G represents the finger-bar to which the guards O are secured. They have a wide opening, m, to the rear of the cutting apparatus, which extends backward to the finger-bar.

In Fig. 7 the blades of the cutting apparatus are represented in a reversed position. n represents the cutters or sickle-knives for cutting the grain. o represents the sickle-bar, and p represents cutters which are secured to the lower side of the blades n.

When the sickle-bar and knives are placed in their proper position within the guard-fingers the cutters p work within the groove in the guard, which is formed by the projections q and r, and the grass, which tends to clog the machine, works out under the cutters and to the rear of the cutting-edges and passes out through the openings m, which are constantly kept clear by the action of the cutters p, which

work against the edges u of the guard-fingers, thus preventing the machine from clogging by damp grass or other material getting in between the cutting apparatus.

Having thus fully described the nature of my invention, what I claim herein as new, and desire to secure by Letters Patent, is—

1. In combination with the angular side bars, 1, of the main frame A, and the inner hinged frame, E, the two short wheel-axes K, when constructed and arranged substantially in the manner and for the purposes herein described.

2. In combination with the open guard-fingers, having spaces m under and to the rear of the cutting-edges of the blades, the clearers p at the lower side of the blades when said clearers operate above the spaces m, and when constructed and arranged substantially in the manner herein described.

ROBERT BROWN.
